By *A. Randolph Jr.* Attorney

UNITED STATES PATENT OFFICE.

JAMES H. SMITH, OF ELZA, GEORGIA, ASSIGNOR TO CHESTER A. WELCH AND WILLIAM F. MILLIGAN, BOTH OF PORTLAND, INDIANA.

SPARK-PLUG INTENSIFIER AND TESTER.

1,409,253.

Specification of Letters Patent. Patented Mar. 14, 1922.

Application filed October 31, 1919. Serial No. 334,828.

To all whom it may concern:

Be it known that I, JAMES H. SMITH, a citizen of the United States, residing at Elza, in the county of Tattnall and State of Georgia, have invented certain new and useful Improvements in Spark-Plug Intensifiers and Testers; and I do hereby declare the following to be a full, clear, and exact description of the invention, such as will enable others skilled in the art to which it appertains to make and use the same.

This invention relates to new and useful improvements in spark plug attachments and has for one of its objects the provision of a device of this character which can be connected to an ordinary spark plug for the purpose of intensifying the spark of the plug and also will indicate if the plug is properly functioning for producing a spark when installed in an engine.

Another object of this invention is the provision of a spark plug intensifier and tester of the above stated character, which will be simple, durable, and efficient, and which may be manufactured and sold at a comparatively low cost.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description, and accompanying drawings, in which—

Figure 1 is a side elevation of a spark plug intensifier and tester constructed in accordance with my invention and illustrating the same applied to a spark plug.

Figure 2 is a perspective view of the intensifier and tester removed from a spark plug.

Referring in detail to the drawings, the numeral 1 indicates as an entirety an ordinary spark plug having the usual central electrode 2 that projects above the upper end of the insulator 3 and receives a nut 4. The foregoing description relates to a well known construction of spark plug to which my invention is adapted to be applied.

A body 5 of substantially rectangular shape has formed upon its lower edge an arm 6 provided with an opening to receive

the central electrode 2. The arm 6 is secured on to the central electrode by means of the nut 4 and said arm and body 5 are constructed of insulating material such as rubber or asbestos. A metallic plate 7 is secured to the body 5 by a bolt 8 which extends through the plate and body and receives a nut 9. The plate 7 overlies the arm 6 in spaced relation thereto and is provided with an opening to receive an adjustable contact 10. The contact 10 is adapted to be moved towards and from the central electrode for the purpose of increasing and decreasing the spark gap between the contact and the electrode. The bolt 8 prior to passing through the plate 7 passes through an opening in a terminal clamp 12 of the usual conductor to a spark plug so that the conductor and the plate 7 are secured to the body by one fastening means.

In operation, when the device is applied to the spark plug, the contact is adjusted to the desired distance from the central electrode and the current will then jump from the contact to the central electrode and from the central electrode to the other electrode of the spark plug in the usual manner, thus intensifying sparks of the spark plug. It is also to be noted that the spark gap provided between the contact and the central electrode will provide an indicator so that a person can readily determine if the spark plug is properly functioning within the engine by the spark appearing between the contact and the central electrode.

By having the device applied to a spark plug as heretofore stated, it will intensify the spark of the spark plug thus assuring the proper explosion of the fuel within the engine, thereby reducing the amount of unburnt fuel in the engine which would be caused by a weak spark. By assuring the complete burning of the explosive fuel within the cylinder it reduces the amount of fuel required to operate the engine and also provides a smoother running engine with an increased power on a less amount of fuel.

While I have shown and described the preferred embodiment of my invention, it will be understood that minor changes in construction, combination, and arrangement of parts may be made without departing from the spirit and scope of the invention as claimed.

Having thus described my invention, what I claim is:—

A spark-plug intensifier, comprising an insulator, one portion of which is thicker than the other portion, there being an aperture formed through each portion of the insulator, means for connecting a wire-terminal to the thick portion of the insulator, means for connecting the thin portion of the insulator to the electrode of a spark-plug,

and means for forming a spark-gap between the terminal and the electrode, all substantially as shown and described.

In testimony whereof I affix my signature in presence of two witnesses.

JAMES H. SMITH.

Witnesses:

T. RUSS SHARPE,
H. C. ROGERS.
